US0D1055274S

(12) **United States Design Patent** (10) **Patent No.:** **US D1,055,274 S**
(45) **Date of Patent:** **** Dec. 24, 2024**

(54) **DRUG DELIVERY DEVICE**

- (71) Applicant: **Avaxzipen Limited**, Abingdon (GB)
- (72) Inventors: **Owen Ryan**, Bray (IE); **David Andrew Grant**, Faringdon (GB); **Ritwik**, Harwell (GB)
- (73) Assignee: **Avaxzipen Limited**, Abingdon (GB)
- (**) Term: **15 Years**
- (21) Appl. No.: **29/836,339**
- (22) Filed: **Apr. 26, 2022**

Related U.S. Application Data

- (62) Division of application No. 35/510,287, filed on Mar. 10, 2020 (U.S. filing date under 35 U.S.C. 384), and having an international filing date of Mar. 10, 2020, now Pat. No. Des. 982,744.

(57) **CLAIM**

The ornamental design for a drug delivery device, as shown and described.

DESCRIPTION

FIG. 1 is a front left perspective view of a drug delivery device;

FIG. 2 is a front right perspective view thereof;

FIG. 3 is a front perspective view thereof;

FIG. 4 is a front left perspective view thereof;

FIG. 5 is a front right perspective view thereof;

FIG. 6 is a front perspective view thereof;

FIG. 7 is a front left perspective view thereof;

FIG. 8 is a front right perspective view thereof;

FIG. 9 is a front perspective view thereof;

FIG. 10 is a front left perspective view thereof;

FIG. 11 is a front right perspective view thereof; and,

FIG. 12 is a front perspective view thereof.

The broken lines in the drawings illustrate portions of the drug delivery device and form no part of the claimed design.

1 Claim, 12 Drawing Sheets
